BRICK VENEER

Giuseppe Sam Benevento, Pittsburgh, Pa.

Application April 4, 1933, Serial No. 664,403

8 Claims. (Cl. 72—19)

This invention relates to improved brick veneer and is particularly adapted for use on the exterior of buildings.

One object of the invention is to provide brick veneer embodying a frame work which is of such construction that the bricks employed will be firmly retained in place within said frame work and also against the wall of the building which is desired to be covered.

10 Another object of the invention is to provide brick veneer which may be secured to a wall or the like in a very simple and highly efficient manner and which securing means will serve to retain the bricks in position.

15 A further object of the invention is to provide brick veneer, the frame work of which may be manufactured in sections so that ready shipping may be effected.

20 A further object of the invention is to provide brick veneer which will closely simulate the real brick and which will be much cheaper in price and very attractive in appearance.

Other and incidental objects of the invention, not particularly mentioned in the foregoing, will 25 be apparent during the course of the following description.

In the drawings,

Figure 1 is a front plan view showing a section of my brick veneer with the brick employed in proper position in the frame work.

Figure 2 is a rear elevation view showing the rear of the frame work with the bricks in position.

Figure 3 is a fragmentary perspective view 35 showing a portion of the frame work ready to receive one of the bricks.

Figure 4 is an enlarged fragmentary transverse sectional view showing the bricks in position in the frame work.

40 Figure 5 is an enlarged fragmentary sectional view showing the frame work with bricks therein secured to the wall, and

Figure 6 is a perspective view showing a corner piece.

45 Referring now more particularly to the drawings, the numeral 1 indicates in general the frame work employed and this frame work is preferably flat and stamped from a blank of heavy galvanized sheet metal. As best seen in Figure 50 3 of the drawings, the frame work comprises top rails 2 and bottom rails 3. Vertical rails 4 are provided at intermittent points. The top rails 2 and bottom rails 3 cooperate with the vertical rails to define brick-receiving recesses 5 and, as 55 will be observed, the vertical rails are arranged

along the top and bottom rails in such a manner that the recesses are disposed in staggered relation to each other which will, when the bricks employed are in place therein, give the appearance of conventional brick construction. Formed 60 on each of the vertical rails 4 are tongues 6 and formed in the top rails are longitudinal nail-receiving slots 7. Nail-receiving openings 8 are provided in the bottom rails 3. It should be understood that the frame work 1 may comprise as 65 many sections as may be desired and the sections are preferably arranged so that they may be readily connected in interlocking relation.

Associated with the frame work is a plurality of preferably baked clay bricks, one of which is 70 indicated in general by the numeral 8'. The

bricks are provided with body portions 9 and are enlarged at their rear portions to define flanges 10. The bricks are placed in the recesses 5 of the frame work and the flanges 10 are adapted 75 to engage the top rails 2 and bottom rails 3.

The tongues 6 are adapted to be bent to engage the rear walls of the bricks 8' for retaining the bricks in rigid position within the frame work. As best seen in Figure 5 of the drawings, it will 80 be understood that when the frame work and bricks are placed against the wall, the bricks will be effectually retained against outward movement by the flanges 10 and will be retained against inward movement, of course, by the wall, 85 a portion of the wall being indicated by the numeral 11. Nails 12 are extended through the openings 7 and 8 in the frame work and are sunk into the wall 11 for effectually retaining the frame work and bricks in position against the wall. It is further emphasized, and clearly 90 shown in Figure 4 of the drawings, that the tongues 6, when bent into proper relation with the rear walls of the bricks, will prevent longitudinal shifting of said bricks in the recesses 5, as well as preventing wobbling of the bricks within 95 the frame work which might possibly be caused by an uneven or warped wall surface. The tongues 6 will, when bent into position, space the bricks from the wall surface and provide an air space between the bricks and the wall which will 100 serve as insulation and help to prevent air from entering the building.

The outer surface of the frame work 1 may be painted to give the appearance of mortar, if desired, and the bricks may be, of course, painted 105 in any desired color, or colors.

As best seen in Figure 6 of the drawings, the corner construction for my veneer embodies a frame work which is indicated in general by the 110

numeral 13. The frame work is, like the frame work 1, preferably formed of heavy galvanized sheet metal and is stamped from a single blank and bent into shape. The frame work 13 is of 5 preferably right angular construction and comprises top rails 14 and bottom rails 15. The frame work 13 also includes vertical rails 16 and, like the frame work 1, the vertical rails 16 are disposed medially of the top and bottom rails so 10 as to define brick-receiving recesses which are in staggered relation to each other, the purpose of this construction, of course, being to give the appearance of conventional brick construction. The rails 14 and 15 are projected to define a 15 tongue which is adapted to fit in recesses defined by the top and bottom rails 2 and 3 of the frame work 1. The frame work 1 will then interlock with the frame work 13. Openings 17 are provided in the frame work 13 and are adapted to 20 receive nails, or other fastening devices. Carried within the recesses defined by the rails 14 and 15 and vertical rails 16 are preferably baked clay bricks 18. The bricks 18 are of angular construction and are adapted to fit in the recesses 25 in the same manner as that employed in conjunction with the frame work 1.

Attention is particularly directed to the fact that, after the frame work 1 and frame work 13 are in position on the wall of a building, and the 30 bricks are in place therein, displacement of the bricks from the frame work will not be possible in view of the fact that the flanges of the bricks cooperate with the tongues on the vertical rails of the frame work for retaining the bricks in 35 position within the frame work. It is also emphasized that as much frame work as may be necessary may be employed and in this connection it should be stated that, in manufacture and shipping the sections will be of a size to permit 40 shipment in large quantities.

It is further emphasized that the veneer will provide an effectual covering for the exterior of a building and will be cheap and very attractive.

Having thus described my invention, I claim:

1. Brick veneer comprising a frame stamped from a single sheet of metal and comprising flat top and bottom rails and vertical rails all disposed in the same vertical plane and defining brick-receiving recesses, and bricks fitted in said recesses and having flanges adapted to bear 45 against the rear faces of top and bottom rails, said frame being adapted to be positioned against the wall of a building whereby the bricks will be clamped between the wall and said frame.

2. Brick veneer comprising a flat elongated frame stamped from a single sheet of material having top and bottom rails and vertical rails defining brick-receiving recesses, bricks fitted in the recesses and having flanges adapted to abut 50 said top and bottom rails, tongues extending rearwardly from the vertical rails and bent into 55 engagement with the rear faces of said bricks and the adjacent surface of a wall for retaining the bricks against longitudinal and rearward displacement, and fastening devices extending through the frame and engaging said wall for retaining the frame in position on the wall.

3. Brick veneer comprising a flat elongated frame stamped from a single sheet of metal and having top and bottom rails defining recesses, 60 bricks fitted in the recesses, and tongues projecting from certain of the rails and adapted to engage the rear faces of the bricks and the adjacent surface of a wall for spacing said bricks 65 from the wall.

4. Brick veneer comprising a frame stamped from a single sheet of material having flat top and bottom rails and flat vertical rails provided with tongues, said top and bottom rails having openings and all of said rails defining brick-receiving recesses, bricks fitted in the recesses and having flanges adapted to bear against the rear face of the top and bottom rails, said tongues being adapted to engage the opposite ends of the bricks and bear against a wall for retaining said bricks in the recesses in spaced relation to said wall, and fastening devices extending through the openings into the wall, said vertical rails being disposed for staggering the recesses and bricks with respect to each other.

5. Veneer brick comprising a frame formed from a single sheet of material having flat oppositely disposed faces and provided with top and bottom rails and vertical rails defining brick receiving recesses, tongues projecting longitudinally from the vertical rails and normally disposed in the plane of the frame, and bricks seated in the recesses and provided with shoulders bearing against the rear faces of the top and bottom rails, said tongues being adapted to be bent inwardly against the inner faces of the adjacent bricks.

6. Veneer brick comprising an elongated frame formed of a single sheet of metal having oppositely disposed flat faces pierced by brick receiving recesses disposed in staggered relation and defining top and bottom rails and vertical connecting rails, tongues projecting longitudinally from the opposite sides of the vertical rails and normally disposed within the lines of the frame, and bricks seated in said recesses and provided with shoulders bearing against the rear faces of the rails, said tongues being adapted to be bent inwardly against the ends of the bricks and thence laterally into engagement with the rear faces of 110 said bricks.

7. The combination with a wall structure, of a brick veneer comprising a flat elongated frame formed from a single sheet of material including longitudinal rails connected by vertical rails defining intermediate brick receiving recesses disposed in staggered relation to each other, bricks fitting in the recesses from the rear face of the frame and provided with shoulders bearing against the longitudinal rails, tongues projecting 120 longitudinally from the vertical rails and bent inwardly against the ends of adjacent bricks and thence laterally against the rear faces of said bricks and in contact with the adjacent surface of the supporting structure for holding the bricks in 125 spaced relation to said supporting structure, and fastening devices extending through certain of the rails and engaging the supporting structure for holding the frame and bricks in position thereon.

8. A corner piece for brick veneer construction comprising a frame stamped from a single sheet of metal, bent intermediate its ends to form angularly disposed portions, each provided with top and bottom rails and vertical rails defining brick-receiving recesses, and bricks of angular construction fitted in the recesses of the angular portions and having flanges adapted to bear against the rear faces of the adjacent top and bottom rails, said frame being adapted to be positioned 140 against a corner of the wall of a building whereby the bricks will be clamped between the wall and said frame.
